CLAIM

The ornamental design for the sport shoe, as shown and described.

DESCRIPTION

FIG. 1 is a right-side, elevation view of the sport shoe, showing my new design;

FIG. 2 is a left-side elevation view thereof;

FIG. 3 is a front view thereof;

FIG. 4 is a rear view thereof;

FIG. 5 is a top view thereof; and,

FIG. 6 is a bottom view thereof.

The broken lines in the figures illustrate portions of the sport shoe that form no part of the claimed design.
